MULTIPLY PAPER BAG

William J. Geimer, Minneapolis, Minn., assignor
to Bemis Bro. Bag Co., Minneapolis, Minn., a
corporation of Missouri

Application March 13, 1939, Serial No. 261,429

1 Claim. (Cl. 229—55)

This invention relates to new and useful improvements in multi-ply paper bags of the general character disclosed in my co-pending application, Serial Number 224,467, filed August 12, 1938.

The present application relates more particularly to the arrangement and location of the pasted areas provided between the plies of the wall portions forming the bag mouth, whereby when the bag has been filled, said pasted areas will permit free rolling and bending of the bag mouth walls in the operation of folding said walls into closing relation, and whereby said pasted areas will not be intersected by the fold lines formed when the bag top walls are folded into closing relation.

An object of the invention is to provide a multi-ply bag having the plies of the walls forming the bag mouth, so interpasted that the bag mouth walls may readily be folded into closing and sealing relation over the contents of the bag body, to provide what is commonly known to the trade as a Deitsaseal closure, and whereby the bag top walls are symmetrically and uniformly folded into closing relation to provide a neatly formed bag closure.

A further object is to provide a bag of the character disclosed, wherein the pasted areas provided between the plies of the bag mouth, are located adjacent to the side edges of the empty bag, when the walls of the bag body are folded into flatwise relation, and the pasted areas at one side edge of the bag being relatively larger than those at the opposite side edge thereof.

Other objects of the invention will appear from the following description and accompanying drawing and will be pointed out in the annexed claim.

In the accompanying drawing there has been disclosed a structure designed to carry out the various objects of the invention, but it is to be understood that the invention is not confined to the exact features shown as various changes may be made within the scope of the claim which follows.

In the drawing:

Figure 1 is a view showing a flattened empty bag with the invention applied thereto;

Figure 2 is a top view of Figure 1;

Figure 3 is a view showing one of the "end walls" of the bag mouth folded inwardly over the contents of the bag, in the initial operation of closing the bag mouth;

Figure 4 is a view showing the oppositely disposed end wall folded over the first folded end

wall, whereby oppositely disposed flaps are provided; and

Figure 5 is a view showing the bag mouth completely closed and sealed.

In the selected embodiment of the invention here shown, there is illustrated in Figure 1, for purposes of disclosure, a conventional form of bag, commonly known to the trade as the "flat type." This bag comprises a body 2 formed from a tube composed of outer and inner plies 3 and 4 of sheet material. Opposite edges of the plies 3 and 4 are overlapped and suitably united to provide a longitudinally extending seam, generally indicated by the numeral 5. When the tube is flattened, as shown in Figures 1 and 2, oppositely disposed side edges 6 and 7 are provided. The seam 5 is shown located adjacent to one of the side edges as, for example, the edge 6, whereby it is less likely to interfere with the rolling and bending of the bag top walls, in the operation of closing the bag mouth. In the drawing, I have shown the walls of the tube as being composed of two plies but it is to be understood that two or more plies may be utilized as desired, without departing from the scope of the invention.

One end of the flattened tube is closed, as indicated by the dotted lines in Figure 1, to provide the bottom 8 of the bag. The bottom shown in the drawing, is of the usual satchel type, and is folded into flatwise relation with respect to the oppositely disposed walls 9 and 11 of the flattened bag, as clearly illustrated in Figures 1 and 2, thereby to facilitate storing the empty bags.

An important feature of the present invention resides in the unique manner of inter-pasting the plies 3 and 4 of the wall portions forming the bag mouth walls, when the bag is expanded to receive a charge. The form of bag shown in the drawing, is rectangular in cross section, whereby the bag mouth is defined by oppositely disposed end walls 12 and 13, and side walls 14 and 15. In the operation of closing the bag mouth, the unseamed end wall 12 of the bag mouth is preferably first folded inwardly over the contents of the bag body, as shown in Figure 3. The end wall 13 is then folded inwardly over the end wall 12, as shown in Figure 4, whereby the side walls 14 and 15 provide oppositely extending flaps 16 and 17. These flaps are subsequently folded inwardly over the end walls 12 and 13, one over the other, as shown in Figure 5, and suitably secured together to completely close and seal the bag.

To thus fold the multi-ply wall portions forming the bag mouth into closing and sealing relation, it is essential that the plies thereof be suitably bonded or pasted together at certain definite locations to prevent the plies from relatively creeping or buckling, when the walls are folded into closing relation, in order to provide a neat bag closure. To thus secure together the plies of the bag mouth walls, a suitable paste is applied between said plies in definitely located areas 18, 19, and 21. All of these pasted areas are located in a common plane. The pasted areas 18 are located adjacent to the side edge 7 of the flattened bag body, and the areas 19 and 21 at the opposite side of the bag body, as clearly illustrated in Figures 1 and 2. In commercial practice, it has been found that best results are obtained by making the pasted areas 19 and 21 relatively larger than the pasted areas 18, or, in other words, they may be approximately twice their size.

Because of the seam 5 being located adjacent to the side edge 6 of the flattened bag body, only one pasted area 21 is provided which, it will be noted, by reference to Figure 2, is located in the wall 9 substantially directly opposite from the seam 5 provided in the wall 11. The pasted areas 19 are spaced inwardly from the seam 5 and pasted area 21, as shown in Figures 1 and 2, a suitable distance so as to clear the points 22 which form the adjacent corners of the bag body, when the empty bag is expanded to receive a charge. It will also be noted that the relatively smaller pasted areas 18 are located between the side edge 7 of the flattened bag body and the points 23, which form the corners at the opposite sides of the bag body, as shown in Figures 4 and 5.

By thus locating the pasted areas 18, 19, and 21, it will be noted that when the bag top walls are folded inwardly over the contents of the bag body into closing relation, said pasted areas will not interfere with the free rolling and bending of the bag mouth walls in the operation of clos-

ing the bag mouth, nor will they be intersected by the fold lines formed when the bag top walls are folded into closing relation, as clearly illustrated in Figures 4 and 5.

The pasted areas 18, 19, and 21 may be inexpensively applied between the plies of the bag walls, as will readily be understood by reference to Figures 1 and 2, and provide a sufficient bond between the plies of the bag walls to prevent relative creeping of the plies of the bag mouth walls in the operation of folding said walls into closing relation.

I claim as my invention:

A bag made from a blank of multi-ply material, said blank being folded upon itself and having its opposed edges secured together to provide a longitudinally extending seam and whereby the blank will form a tube, one end of said tube being closed to provide the bottom of the bag and said tube being flattened to provide two walls disposed in flatwise relation with the longitudinally extending seam disposed adjacent to one of the side edges of the flattened bag body, a suitable paste applied in small areas between the plies at the seam side of the flattened bag, relatively smaller pasted areas at the opposite side of the bag, said longitudinally extending seam and pasted areas being so located that when the bag is expanded to receive a charge, said seam and one of said pasted areas will be disposed in one end wall of the bag body and two of said pasted areas in the side walls of the bag body adjacent to said seamed end wall, and the relatively smaller pasted areas being located in the opposed end wall of the expanded bag body, and all of said pasted areas and the seam being so arranged that none of the fold lines formed by folding the bag top walls into closing relation will intersect any of said pasted areas, thereby facilitating the operation of folding the bag top walls into closing relation and whereby the perimeter of the closed bag top will be symmetrical in appearance.

WILLIAM J. GEIMER.
